UNITED STATES PATENT OFFICE

113,853

DESIGN FOR A FINGERNAIL BOWL

Mike Ragan, Los Angeles, Calif.

Application September 3, 1938, Serial No. 79,734

Term of patent 14 years

To all whom it may concern:

Be it known that I, Mike Ragan, a citizen of the United States of America, residing at Los Angeles, in the county of Los Angeles and State of California, have invented a new, original, and ornamental Design for a Fingernail Bowl, of which the following is a specification, reference being had to the accompanying drawing, forming part thereof.

Fig. 1 is a perspective view of a fingernail bowl showing my new design;

Fig. 2 is a bottom plan view thereof.

I claim:

The ornamental design for a fingernail bowl, as shown.

MIKE RAGAN.
